PAPER-GAGE FOR TYPE-WRITING MACHINES.

1,199,462.

Specification of Letters Patent. Patented Sept. 26, 1916.

Application filed April 8, 1913, Serial No. 759,583. Renewed February 1, 1916. Serial No. 75,627.

To all whom it may concern:

Be it known that I, EDWARD B. HESS, a citizen of the United States of America, residing in the borough of Brooklyn, county of Kings, and State of New York, have invented a certain new and useful Improved Paper-Gage for Type-Writing Machines, of which the following is a specification.

This invention relates to a side paper gage 10 coöperating with the feed table.

Its object is to provide a simple and effective gage that may readily be adjusted to operative position on the table or to a position in rear of the table out of observation, or 15 substantially so, of the operator seated at the front of the machine.

A further object is to provide a gage which, while readily adjustable in the direction of length of the table when in inoperative position, is when in operative position held comparatively against movement longitudinally of the table—thus among other advantages preserving the 20 surface of the table from defacement.

25 In the accompanying drawing: Figure 1 is a transverse section, looking from the right of the machine, of the paper table and associated parts showing a gage in operative position: Fig. 2, a like view showing a gage in inoperative position: Fig. 3, a plan view showing one end of the paper table and the gage in inoperative position: Fig. 4, a rear elevation showing the gage in inoperative 30 position, the table being omitted: Fig. 5, a front elevation omitting the table and showing the gage in operative position: Fig. 5^a is 35 a detail view of the slotted sleeve forming part of the gage. Fig. 5^b is a detail view in elevation of the stop and locking plate, 40 forming part of the mechanism. Fig. 6, a front elevation of a paper table with a gage in operative position adjacent each end of the table.

The drawing shows a paper table adapted 45 to be swung rearwardly, as disclosed in the patent of Edward B. Hess, No. 958,497, granted May 17, 1910. That is to say, the paper table 1 having upper and lower curled edges 2, 2, is carried by angular arms 3, 3, 50 one at each end, attached to stiffening plates or ribs 4 on the under face of the table at or adjacent each end and secured thereto by screws 5. The arms 3 have at their lower ends co-incident apertures or bearings 6

adapted to turn upon or with a suitable support so that they, with the paper table and attached parts, may be swung rearwardly for the purposes disclosed in said patent. The present invention, however, is in no way dependent upon such a swinging movement 60 of the table but is on the contrary applicable to paper tables of various constructions mounted in ordinary ways. For the purpose of illustrating such an arrangement it may be assumed that the arms 3 are cut off 65 at the dotted lines α and that the paper table is supported in any usual appropriate way. Between the arms 3 extends a shaft 7 having a flat side 8 as shown in Fig. 1 which flat side is shown as the bottom or under surface 70 of the rod. Fitted to slide and turn on the rod 7 is a short sleeve 9 having a slot 10 (dotted lines Fig. 3) extending part way through the sleeve from one end thereof. Projecting from one wall of said slot is an 75 integral part 11 formed with a circular hub 12 at its outer end with a bore the axis of which is at right angles to rod 7. In the bore of the hub 12 is rotatably fitted a stud 80 shaft projection 13 fixed in or integral with a plate 14' which is integral with and extends laterally from the paper gage 14. Fixed to the end of the stud extension 13 by means of a screw bolt 15, or otherwise, is an angularly shaped plate 16 that may appropriately be called a stop and locking plate, the contour of which is clearly seen in Fig. 4, and the edge of which works in the longitudinal slot 10 in the sleeve 9.

Within the hub 12, surrounding the stud 90 shaft 13 and lying in an enlargement of the bore is a coiled spring 17 one end of which is attached to the plate 14' and the other to hub 12. The reaction of this spring tends to carry the paper gage 14 to a position parallel with the shaft 7. On the sleeve 9 is a stop projection 18, which in the normal inoperative position of the gage (Figs. 3 and 4) abuts against the upper coiled edge of the table and so determines the position of the gage when lying parallel with the shaft 7 and somewhat below the upper edge of the paper table. In this position the gage is substantially unobservable by one sitting in front of the machine, or at least it is quite 100 out of the way. At this time a projection α of the stop and locking plate 16 has been 105 swung upwardly by the reaction of spring

17, or by strain upon the gage, and lies in the slot with the square surface *b* of its end opposite and closely contiguous the flattened face 8 of shaft 7. The gage and its support 5 (sleeve 9) may now be slid along the rod with convenient ease. When the gage 14 is swung upwardly, the inner rounded nose or corner of plate projection *a* permits it to freely clear the shaft and as the plate 16 rotates with the gage, its corner *d* passes into the inner end of slot 10 but is not of sufficient radius to engage the flat side of the rod and as the movement continues until the gage 14 is at right angles to shaft 7, a shoulder *e* 10 on the bottom edge of the plate, as seen in Fig. 4, comes against the outer face of the sleeve 9, as seen at Fig. 5. This position of the parts having been reached, the gage member 14 may now be pressed downwardly 15 and the hub will turn upon shaft 7 until the gage is in contact with the surface of the paper table, standing at right angles thereto with the top surface of the plate 14' flush with the front surface of the table. In this 20 position, the gage device is held and may not be moved longitudinally of the shaft 7 except by the exertion of unusual strains because the flat surface *f* of plate 16 extending between the angular corner *d* and shoulder *e* 25 is of such radius as that (while it does not engage the flat face of shaft 7) it engages with sufficient friction the circular part of the shaft. Such substantial fixity of the gage is most desirable because it practically 30 cannot be adjusted laterally of the table without being first elevated and allowed to return to its normal inoperative position. In this way, there is eliminated unsightly 35 defacements of the surface of the paper 40 table.

I claim:

1. The combination with the paper table of a typewriting machine, of a paper gage adapted to coöperate with the table and 45 pivotally movable about two axes one perpendicular to the table and the other parallel with the transverse length of the table, and devices carried by said gage for preventing sidewise movement thereof across the 50 face of the table when the gage is in operative position on the table.

2. The combination with the paper table of a typewriting machine, of a paper gage adapted to coöperate with the table and 55 pivotally movable about two axes one perpendicular to the table and the other parallel with the transverse length of the table, and locking devices carried by said gage for preventing it from moving about an axis 60 perpendicular to the table when in operative position on the table.

3. The combination with the paper table of a typewriting machine, of a rod disposed longitudinally thereof in fixed relation thereto and in rear thereof, said rod having a

flattened under face, a gage carrier turning about the rod and longitudinally movable thereon, a gage having a bearing in the carrier, the axis of which is transverse to the carrier, a stop surface movable with the gage and abutting against the flat surface of the rod when the gage is in said normal inoperative position whereby the gage may be turned upwardly to a position transverse to the table, a stop movable with the gage and limiting such upward movement whereby the gage may be turned down upon the table by rotation of the carrier on the rod, and a surface movable with the carrier or gage in the last named movement of it that 70 bears upon the circular face of the rod when the gage has been turned to operative position upon the table whereby the carrier is held frictionally against movement endwise on the rod.

4. The combination with the paper table of a typewriting machine, of a paper gage adapted to coöperate with the table and pivotally movable about two axes one perpendicular to the table and the other parallel with the transverse length of the table, locking devices carried by the gage permitting it to move freely about an axis perpendicular to the table when in inoperative position but which prevent it from moving 75 about said axis when in operative position on the table, and a spring coöoperating with said locking devices for automatically moving the gage about an axis perpendicular to the table after the gage has been raised and 80 moved rearwardly from the table about an axis parallel with the transverse length thereof.

5. The combination with the paper table of a typewriting machine, of a rod mounted 85 in rear of and longitudinally thereof in fixed relation thereto, a carrier mounted to turn about the rod and move longitudinally thereon, a gage pivoted upon the carrier on an axis transverse to the rod whereby the gage may be moved upwardly to a plane transverse to that of the table, a stop for limiting such movement whereby the gage 90 may be moved toward the surface of the table in operative relation thereto and a stop acting in the last named position of the gage to prevent movement of the gage about its pivotal axis on the carrier.

6. The combination with the paper table of a typewriting machine, of a rod in rear 95 of the table disposed longitudinally thereof and in fixed relation thereto, a gage carrier mounted to turn about the rod and adjustable longitudinally thereof, a gage pivotally mounted upon said carrier to turn in an upward direction whereby the gage may be turned upwardly to a position transverse to the table and then be turned down upon the table by movement of the carrier around the rod, and a spring, the reaction 100

of which tends to turn the gage to a position parallel with the longitudinal length of the table.

7. The combination with the paper table 5 of a typewriting machine, of a rod disposed longitudinally thereof in fixed relation thereto and in rear thereof, a gage carrier mounted upon said rod to turn thereon and be longitudinally adjustable thereon, a gage 10 pivoted upon said carrier and disposed, when in inoperative position, lengthwise of the rod, stop means for holding the gage in such normal inoperative position, a pivotal connection of the gage upon the carrier 15 whereby the gage may be turned upwardly to a plane transverse to that of the table from which position it may be turned downwardly upon the surface of the table by rotation of the carrier about the rod, and a 20 spring, the reaction of which tends to turn the gage to a position parallel with the longitudinal length of the table.

8. The combination with the paper table 25 of a typewriting machine, of a rod disposed longitudinally thereof in fixed relation thereto and in rear thereof, said rod having a flattened under face, a gage carrier turning about the rod and longitudinally movable thereon, a gage having a bearing 30 in the carrier, the axis of which is transverse to the carrier, a stop surface movable with the gage and abutting against the flat surface of the rod when the gage is in said normal inoperative position whereby the 35 gage may be turned upwardly to a position transverse to the table, a stop movable with the gage and limiting such upward movement whereby the gage may be turned down upon the table by rotation of the carrier 40 on the rod, a surface movable with the carrier or gage in the last named movement of it that bears upon the circular face of the rod when the gage has been turned to operative position upon the table whereby 45 by the carrier is held frictionally against movement endwise of the rod, and a spring, the reaction of which tends to turn the gage to a position parallel with the longitudinal length of the table.

50 9. The combination with the paper table of a typewriting machine, of a longitudinally adjustable rotatable carrier mounted adjacent the upper edge of the table and in rear thereof, a paper gage pivoted on the 55 carrier on an axis transverse to the paper table whereby the gage may be moved upwardly from operative relation to the paper table and then be moved downwardly on

said pivotal connection to a position in rear of the paper table and parallel therewith, 60 and a spring, the reaction of which tends to turn the gage to a position parallel with the longitudinal length of the table.

10. The combination with the paper table 65 of a typewriting machine, of a longitudinally adjustable rotatable carrier mounted adjacent the upper edge of the table and in rear thereof, a paper gage pivoted on the carrier on an axis transverse to the paper table, whereby the gage may be moved 70 upwardly from operative relation to the paper table and then be moved downwardly on said pivoted connection to a position in rear of the paper table and parallel therewith, 75 stop means coöperating with the carrier and gage to maintain them in appropriate positions, and a spring, the reaction of which tends to turn the gage to a position parallel with the longitudinal length 80 of the table.

11. The combination with the paper table 85 of a typewriting machine, of a rod mounted in rear of and longitudinally thereof in fixed relation thereto, a carrier mounted to turn about the rod and move longitudinally 90 thereon, a gage pivoted upon the carrier on an axis transverse to the rod whereby the gage may be moved upwardly to a plane transverse to that of the table, a stop for limiting such movement whereby the gage 95 may be moved toward the surface of the table in operative relation thereto, a stop acting in the last named position of the gage to prevent movement of the gage about its pivotal axis on the carrier, and a spring, 100 the reaction of which tends to turn the gage to a position parallel with the longitudinal length of the table.

12. The combination with the paper table 105 of a typewriting machine, of a paper gage adapted to coöperate with the table and movable about two axes, the movement about the first axis serving to bring the gage into a plane transverse to the table and the movement about the second axis 110 serving to bring the gage down upon the table in operative relation thereto, and means for locking the gage when in the latter position against movement about said first axis.

In testimony whereof, I have hereunto subscribed my name.

EDWARD B. HESS.
